TIME CONTROLLING MECHANISM

Carl Erik Jean Nilson, Storgatan, Angelholm,
SwedenApplication January 7, 1946, Serial No. 639,661
In Sweden January 26, 1945.

6 Claims. (Cl. 161—2)

1

The present invention relates to an apparatus composed of a number of wheels and/or movable discs, which on moving actuate a movable part comprised in the apparatus, thus setting this part in motion. Said motion can be used, for instance to close a circuit at predetermined times, in order to give a signal for switching on light, starting a motor or the like. It can also be arranged for actuating, electrically or mechanically, other apparatus, thus regulating said apparatus, e. g. for starting said second apparatus, changing its motion direction, registering a certain condition in the apparatus a. s. o.

Such an apparatus can for instance be a time registering device, the function of which is such, as will cause a regulation at certain predetermined times in order to mark different periods, a. s. o., in different ways. In this connection, the apparatus can be arranged so that the regulation can take place at different times for different days. If for instance the apparatus is used for time signalling in a factory, where the working-time is different on Saturdays than on the other days of the week, the apparatus can be set so that the signals are adjusted to the times determined for each day.

The accompanying drawings show an embodiment of an apparatus conceived according to the invention, said embodiment being fit for use in connection with time control, time signalling, etc.

Fig. 1 is a side view of the apparatus and Fig. 2 shows a front view of the same. Figs. 3, 4 and 5 show details of the apparatus for a more clear understanding of its working system.

The frame of the apparatus consists of a pair of plates 1 and 2, Fig. 1, bound together by means of a pair of bolts 3 and 4. A shaft 5 is fastened on said frame, the shaft furthermore supporting a cylinder 6, which can turn round said shaft, said cylinder consisting of a number of discs 7 separated by washers 8. The discs 7 and washers 8 are kept together by means of rivets 9 and a centre tube 10, being the layer of the cylinder 6.

The discs 7 are at their periphery provided with grooves 11, into which pins 12 can be inserted. The pin 12 ought to be cleft at one of its ends. Hereby, there arises a certain resiliency, which serves to retain the pin on inserting it into its groove 11 in the disc 7. The other end of the pin 12 is provided with a head which, on the pin

2

being inserted into the groove 11 in the disc 7, lies outside the periphery of said disc, a protuberance thus being formed on the periphery of the disc. In order to drive the cylinder 6 round its shaft 5, said cylinder 6 is provided with a toothed wheel 13, which meshes with a pinion 14, which is driven in a suitable manner from another apparatus for time signalling, conveniently a clock mechanism.

- 10 10 The movable part is made of an arm 15, which moves round an axis 16. In the embodiment shown on the drawing the arm 15 is made as an angle and provided with an axis 17 fastened on said arm, a roll 18 being cradled on said axis.
- 15 15 The roll is composed of a number of discs 19, spaced by washers 20 kept together by rivets 21 and a bushing 22. The discs 19, which in the roll 18 are equal in number to the discs 7 in the cylinder 6, are provided at their periphery with protuberances 23, which have been placed so on riveting the roll, that the protuberances on the different discs are offset in relation to each other. Between the protuberances of the first and second discs, there is a certain angular distance, between the second and third discs an equal angular distance, a. s. o. When the apparatus is in function and the roll 18 is being turned round step by step, the discs 19 can in their proper turns and only one at a time by means of some of their protuberances 23 mesh with the corresponding disc 7 in the cylinder 6 by means of the arm 24. The roll 18 is placed so in the apparatus, that its discs 19 come right in the same plane as the corresponding discs 7 in the cylinder 6. Between the
- 20 20 25 25 30 30 35 35 40 40 45 45 50 50 cylinder 6 and the roll 18 there are arms 24, one for each disc in the cylinder, resp. the roll, placed so, that they come in the same plane as their respective discs, and turningly cradled on the axis 16. Said arms 24 serve to receive the friction appearing against the roll on the cylinder being turned round and to prevent the roll from following said motion.

Further, the roll 18 is provided with a toothed wheel 25, which is meshed with another toothed wheel 26 cradled on the axes 16. The cylinder 6 has a disc 27 running against said toothed wheel, said disc being provided with a tooth 28, Fig. 5, which, after the cylinder having revolved one turn, actuates the toothed wheel 25 and moves it forward one step. Thus the roll 18 also turns one

step corresponding to the angle between the protuberances 23 between two discs 19 lying near each other in the roll 18. The arm 15 is held in such a position by means of a spring 29, that the roll 18 rests permanently against one of the arms 24, which are thus pressed against the cylinder 6.

The embodiment shown on the drawing refers to an apparatus for making regulations automatically at predetermined times in some other apparatus, sending time signals or the like. The apparatus is hereby driven in a suitable manner, for instance by a clock mechanism, the motion of which is propagated by means of the toothed wheel 14, Fig. 1, to the toothed wheel 13 fastened on the cylinder 6, which is thus turned round its shaft 5. The motion may either be smoothly continual or arranged step by step so that the cylinder 6 is turned an equal space for each time period. The time periods may be minutes, tenth parts of the hour or another desired division of time. The division of the grooves 11 in the discs 7 must correspond to the turning angle of the cylinder 6 for its motion during a time period. If thus the first groove at the initial position of the cylinder is lying right in the same plane as the head of the arm 24, the second groove must, after a turning motion forward corresponding to a time period, be lying at said place, after a second forward turning the third groove at said place, a. s. o.

The protuberances 23 on the roll 18 are arranged so, that only one at a time can be right in the same plane as the head of one of the arms 24. On the cylinder 6 having been revolved one turn, the tooth 28, Fig. 5, on the disc 27 meshes with the toothed wheel 26 and turns it forward one step. The toothed wheel 25, which is fastened on the roll 18 and meshes with the toothed wheel 26, is thus also drawn forward one step, and so is the roll 18, the nearby lying disc 19, Figs. 1 and 2, thus meshing with its respective arm 24 by means of its protuberance 23. In said way all the protuberances of the roll 18 will mesh one after the other with their respective arms 24, which may thus be actuated by possibly inserted pins 12 in the discs 7 in the cylinder 6, which rests against them.

The grooves 11 in the discs 7 are sixty in number in each disc in the described embodiment of the apparatus. If the time periods are to be tenth parts of the hour and the turning forward of the roll corresponds to the angle between two grooves in the disc 7, the roll will then revolve one turn during six hours and four turns during twenty-four hours.

To mark each tenth part of the hour, four discs 7 are needed in the cylinder 6, said discs one after the other being able to be meshed with corresponding arms 24 and discs 19 in the roll 18. Owing to the roll 18 being moved one step forward for each turn of the cylinder 6 corresponding to the dividing angle between the protuberances 23 on the discs 19 lying close to each other in the roll 18, the discs 19 will, for each such motion forward of the roll, one after the other mesh with the corresponding disc in the cylinder 6 by means of their protuberances 23. After the cylinder having revolved four turns the pair of discs will again mesh and thereafter, for each turn of the cylinder, the second, third, fourth a. s. o. pair of discs for each day on which the time signals are to be given at the same time. If the signals are to be given at other times on certain days, four further discs will be inserted in the cylinder and as many corresponding discs

in the roll for each day, on which the signals are to be varied.

The embodiment shown on the drawing shows an apparatus, in which the signals are to be given at the same time six days of the week and at other times one day of the week. As well the cylinder 6 as the roll 18 are provided with two sets of four discs each. The roll 18 is arranged so by said embodiment, that it revolves one turn a week on its above described motion forward step by step. The divisions between the protuberances are arranged so, that the first four discs mesh with the corresponding discs in the cylinder 6 during six days of the week in the above described way, and the second set of four discs on the seventh day.

During the revolving of the cylinder 6, the grooves 11 will on established times regularly pass the heads on the arms 24 and thus each groove represent a certain time. In the grooves corresponding to the times, on which the signals are wished to be given, the pin 12 is inserted. On the pin 12, Fig. 4, during the revolving of the cylinder 6, passing some of the arms 24, which is held meshed against the cylinder 6 by means of the protuberance 23 on the disc 19, the head of the pin 12 will actuate the arm 24 and thus also the roll 18, which is then radially removed from the cylinder 6. The movable part, the arm 15, which is connected to the roll 18 by means of the axis 17, then revolves round its axis 16, and said motion can be used for actuating a suitable device for sending a signal, etc. On the further revolving of the cylinder 6, the pin 12 passes the head of the arm 24, the movable part, the arm 15, together with the roll 18 then being by means of a spring 29 drawn back its initial position, where it remains until the next pin 12 passes, the same motion then repeating itself.

Fig. 3 shows the position of the arm 24 between the protuberances 23 on the discs 19 in the roll 18, which are not meshed with the head of the arm 24 by means of some of the protuberances 23. As appears from the drawing the pin 12 in the cylinder 6 may in said case pass the head of the arm 24 without the roll 18 being actuated, since the arm has enough free space in the recesses between the protuberances 23 in the discs 19.

Though I have described an apparatus, in which the cylinder 6 and the roll 18 have been composed of a number of discs, the cylinder as well as the roll may naturally be made solid and provided with holes for the pins 12, or the discs being ring shaped, etc.

55 I claim:

1. In combination, a cylinder rotated at a speed proportional to the elapse of time, a movable member, a roll rotatably mounted on said member and movable therewith, means for imparting step-wise rotary movement to said roll during rotation of said cylinder, peripheral projections on said roll, and pins settable in selected positions on the periphery of the cylinder and coacting, in predetermined relative positions of the cylinder and roll, with said projections to displace said roll and actuate said movable member.

2. An arrangement as claimed in claim 1 wherein the roll is moved one step during each complete revolution of the cylinder so that for each step-wise movement of the roll the projections thereon are moved into operative relation to the projections in selected sequence.

3. An arrangement as claimed in claim 1 75 wherein movable arms are arranged between the

cylinder and the rolls through which the pins coact with the projections.

4. An arrangement as claimed in claim 1 wherein said cylinder includes a plurality of discs having peripheral grooves in which said pins are engageable.

5. An arrangement as claimed in claim 1 wherein said roll includes a plurality of discs carrying said projections.

6. An arrangement as claimed in claim 1 wherein said movable member is constituted by an arm pivotally mounted at a point removed from the axes of said cylinder and said roll.
